MATTRESS

Irving Magaril, Brooklyn, N. Y.

Application July 7, 1937, Serial No. 152,352

1 Claim. (Cl. 5—351)

This invention relates to a new type of mattress construction comprising interchangeable layers of various fillers and interchangeable parts.

Broadly, it is an object of this invention to produce a mattress of simple and durable construction that can be manufactured at a reasonable cost.

More specifically, it is an object of this invention to provide a sanitary and hygienic mattress that is comfortable, easy to assemble and to take apart, thus being easy to clean.

Another object of this invention is to produce a mattress which will remain dustless and odorless because of its separate layers allowing free access of air circulation.

Another object of this invention is to produce a mattress cover that will contain various layers comprising the mattress, the mattress covers being removable and easily washed and ironed and will retain its original size and shape because it will be made of pre-shrunk and durable material, thus making it sanitary.

Another object of this invention is to produce a mattress that will be suited to the individual requirements of the person since the layers are interchangeable, being composed of an inner spring unit, cotton pad or cotton felt-pad, kapok or hair pad or any combination of such pads or any thickness of such pads to comprise the proper hardness or softness desired by the individual.

Any combination of pads of different types and thicknesses may be used with or without an inner spring unit combination pad.

Another important object of this invention is that such interchangeable pad mattress can be used by persons susceptible to hay-fever and asthma since many such people suffer because of the various types of mattress fillers used.

Another object of this invention is to produce a neat looking and perfect fitting mattress because of the adjustable and perfect fitting cover.

Another object of this invention is to produce decorative and effective mattress covers because of the interchangeable nature of such covers.

Another object of this invention is to produce a perpetual and interchangeable mattress economical to maintain at an inexpensive cost of upkeep, since the various pads can be purchased separately.

Another object of this invention is to produce a mattress cover which can be easily cleaned in the event of frequent soiling.

Another object of this invention is to produce interchangeable pads, half the width of a double sized bed, so that one person can sleep on a com-

bination of soft pads and an inner coil spring unit, while the other can sleep on a hard combination of pads including a wood board beneath such pads, which would be advantageous for curvature of the spine.

Another object is to improve the appearance of the bed by having an apron attached to the lowermost cover or pad-cover that will cover the bed spring to give the appearance of a box spring, at the same time being hygienic and inexpensive.

In the accompanying drawing, forming a material part of this disclosure:—

Fig. 1 is a perspective view showing the cover open at the corner, said cover containing an inner spring unit with a pad top and bottom.

Fig. 2 is a perspective view showing two pads, acting as top and bottom, and a side cover all in co-acting relationship.

Fig. 3 is a fragmentary transverse sectional view of multiple layers within a mattress cover.

Fig. 4 is a fragmentary transverse sectional view showing a pad, top and bottom, and flaps acting to form a cover to receive an inner spring unit or other pads.

Fig. 5 is a section showing a division along the longitudinal center of the bed, the right side showing an inner spring unit containing a pad, top and bottom; the left side showing three pads and a board below the third pad, all within a cover.

Fig. 6 is a perspective view of a variation of a mattress cover in co-acting relationship.

Referring to the drawing in Fig. 1, numeral 10 represents the top of the mattress cover having side 11 sewn thereto along edge 35, said side containing a series of fasteners 12, along the outer edge to receive opposite half 14 of said fasteners which are attached to one end of fastening strips 13. A similar side 15 acts as the lower side of the mattress cover and is attached by sewing or other means along edge 16 to the bottom of the mattress cover 17. Along edge 16 there may be attached an apron 18, which may be either flat or pleated. This apron will fall around the bed spring (not shown) to improve the appearance of the bed. It is not essential but is used for the purpose of appearance only. Along the edge of side 15, there is attached a series of fasteners 12, to receive the opposite fastener which is attached to the opposite end of strip 13.

The entire cover is made in various sizes to conform to the standard size beds, either single, three-quarters or double. This cover may also be made in special sizes. This cover is made wide enough to receive a series of pads 19 and 20.

28 and inner spring unit 21, as shown in Fig. 1. Pads 18 and 28 may be constructed of different thicknesses and fillings, such as cotton, cotton felt, kapok, hair, excelsior, fibre, moss, or any combination of such fillers for different hardness or softness. Such pads are interchangeable so that a person may choose the most desirable combination to give the most beneficial result for the individual person.

10 In Fig. 2, 22 represents a cover pad which may be used as the top and bottom of a mattress, such pads contain snaps along the side edges for fastening to strips 23 secured along the edges of side 24. Between pads 22, which may be of any type of construction or hardness, there may be placed several pads containing different fillers or pads or an inner spring unit, depending upon the degree of hardness that the individual prefers. The top and bottom 22 may also represent a cloth cover instead of a pad and the side edges 25 and 26 may be of cloth so that the entire unit may act as a mattress cover.

In Fig. 3, cover 10 is fastened by strip 13, containing fastening means 14 which may be fastened to lower cover 15 and the entire cover may contain multiple layers of interchangeable pads containing different types of fillers for different degrees of hardness. Fig. 3 shows four layers; however, there may be less than four or more than four, depending upon how thick such layers are made and how much pressure it is desired to place upon such layers.

Fig. 4 shows a pad 27 containing a cloth flap 28. The upper and lower portion is similar and may be joined together by fastening strips 13. Between the layers pads 27, containing different fillers or an inner spring unit, may be placed to produce a mattress of interchangeable layers and different degrees of hardness. The top and bottom may be joined together by any type of fastening means.

Fig. 5 shows a section of a bed divided along its length so that two people can sleep in the same bed; each side, however, may contain pads of different thicknesses and resiliency or an inner spring unit so that each person will have half or any division of the bed suited to his or her individual requirements. For instance, the right part may contain an inner spring unit with a pad 50 above and below the inner spring unit, the entire right part of the bed being comparatively soft. The left side may contain two or more comparatively hard pads with a board 34 beneath

the bottom pad so that the left side would be very hard. The left side of the bed would be very beneficial to a person having curvature of the spine. Such pads may be interchangeable both for different degrees of hardness and for sanitary purposes. All the pads or inner spring units are placed between the cloth cover 18 and 17.

During different seasons of the year it may be desirable to change the inner pads to produce a mattress that may be cooler or warmer to sleep upon. It is also desirable to change pads for sanitary reasons and to keep such a mattress dust-proof. The covers may be made of pre-shrunk materials and may be frequently washed so that such cover will be sanitary and at the same time will keep its original shape.

Fig. 6 pictures the top 38 of half of a mattress cover having two deeper sides 39 and two strips 31. The other half of the mattress cover is similar to the upper half but inverted. The deep sides 39 and the strips 31 contain fasteners 14 at the edges. When the two halves of the mattress cover are to be fastened together, the deep sides 39 are fastened to the strips 31 by fastening means. Any type of pads or inner spring units may be placed within this cover to obtain different degrees of hardness to suit the individual.

It is to be understood that I do not limit myself to the exact construction shown in the drawing and the right is reserved to make all changes and modifications that will fall within the scope of the appended claim.

These and other advantages, capabilities and features of my invention will appear from the subjoined detailed description and more particularly pointed out in the claim appended hereto.

I claim:

In a mattress, separable top and bottom pad members, each comprising filling material enclosed between fabric covers, a filler unit enclosing band consisting of a fabric strip extending around the side and end edges of the mattress, a series of strips extending outwardly from the upper and lower edges of the band, and complementary fastener elements carried by the strips and the edge portions of the top and bottom pad members for detachably securing the pad members to the band to provide a closed filler unit receiving housing.

IRVING MAGARIL.
